UNITED STATES PATENT OFFICE.

HAROLD ELIJAH WHITE, OF MONTCLAIR, NEW JERSEY, ASSIGNEE TO CROCKER-WHEELER COMPANY, OF AMPERE, NEW JERSEY, A CORPORATION OF NEW JERSEY.

CENTRIFUGAL ELECTRIC SWITCH.

Application filed November 15, 1919. Serial No. 338,230.

To all whom it may concern:

Be it known that I, HAROLD ELIJAH WHITE, a citizen of the United States of America, and a resident of Montclair, in the county of Essex and State of New Jersey, have invented certain new and useful Improvements in Centrifugal Electric Switches, of which the following is a specification.

Single phase induction motors, to which this invention is especially applicable, comprise two windings, one of which is required to be energized only during starting and the circuit of which it is desirable to open when the motor has attained a certain speed.

The object of this invention is to provide an automatically operated rugged and durable switch especially applicable for controlling this circuit, and to make it of such construction that it may be housed within the frame of the motor and the contact ring thereof carried by the rotor shaft. Further objects are to provide for the maintaining of the electric circuit through contacts which do not slide on each other while carrying current, but have a sufficient sliding contact during stopping to keep the contact surfaces in good condition. A further object is to provide for a quick opening of the contacts without chattering.

In the accompanying sheet of drawings which forms a part of this application—

Figure 1 is an end view of a switch embodying this invention, the end frame of the motor, with which it is used being omitted, and the contact supports and contact ring being partly broken away.

Figure 2 is a section through the axis of the motor showing the contacts closed.

Figure 3 is a side view showing the contacts open.

Figure 4 is a diagram of the electrical circuits.

The switch is shown as applied to a single-phase motor with split-phase windings. The motor comprises a squirrel-cage rotor carried on a shaft 6, a power winding 7, and an auxiliary winding 8, used in starting, both of which derive energy from the same source of supply, as shown, by being directly connected through a connecting switch 9. The power winding is supplied with current both in starting and in running at full speed, and the auxiliary winding is energized in addition in starting but the circuit

through it is broken when the motor is running above a certain speed in order to save current.

To automatically break this circuit through the auxiliary winding a centrifugally operated switch is provided. The switch comprises two elements one of which is a pair of contacts 10, 10 which are in the branch circuit through the auxiliary winding. The other element of the switch is a contact ring 11 which is mounted on an insulating disk 12. One of the elements of the switch and preferably the pair of contacts is mounted through insulating strips 13, 13 on the inner side of one of the end frames 14 of the motor, and the other element, preferably the contact ring, is carried by a revolving element of the motor, preferably the rotor shaft. The insulating disk which bears the contact ring is carried by a sliding sleeve 15, and the sliding sleeve is carried by the motor shaft, and slideable thereon. The sleeve has a shoulder 16 which forms a stop against which the disk carrying the contact ring bears when the switch is open, a spring 17 pressing the disk against this shoulder. When the switch is closed this spring presses the contact ring against the pair of contacts.

Centrifugal weights 18, 18 are guided on transverse pins 19, 19, and the pins are held by a bracket 20 which is attached to the rotor core by screws. The weights have a straight line movement only and a minimum of space needs to be provided between the squirrel cage and the end frame to afford them the necessary freedom. Oblique links 21, 21 connect the weights with the sliding sleeve. Tension springs 22, 22 draw the weights together. These springs are of light wire with coils originally wound close so that they are under considerable initial tension when the weights are together and the tension will increase less rapidly than the centrifugal force as the weights separate. In consequence, when the speed of the rotor becomes sufficient to start the weights they will at once fly out to their limit of movement. Owing to the sliding movement between the sleeve and the contact ring, the separation of the contacts is not effected at the moment when the weights start to move outwardly from the axis of the rotor, but the separation is effected midway of the outward movement when the shoulder stop 110

strikes the insulating disk, and is therefore instantaneous and without chattering.

On closing the connecting switch, the motor being at rest, current will start to flow through both the power winding and the auxiliary winding, and the motor will start but the contact ring will not turn and will bridge the pair of contacts and conduct current between them without rubbing. When a certain speed is reached the switch opens and the current continues only through the power winding. The centrifugal switch closes ordinarily only when the current has been cut off from the power winding and the motor is slowing down, and it follows that there will be no current flow through the centrifugal switch at the time of its closing.

As just before closing the contact ring will be revolving with the rotor there will be a slight rubbing of the contacts when closing to keep them in condition, and this takes place when there is no flow of current between the contacts.

What I claim, is—

In combination with a revolving element, an electric switch, comprising stationary contacts and a contact ring slideable on the revolving element, transverse pins mounted to revolve with the revolving element, centrifugal weights guided on the pins, and oblique links connecting the weights and contact ring, substantially as described.

HAROLD ELIJAH WHITE.
